PREVENTION OF PARASITIC OSCILLATIONS

Original application filed November 9, 1928, Serial No. 318,194. Patent No. 1,785,819, dated December 23, 1930. Divided and this application filed March 27, 1930. Serial No. 439,389.

This invention relates to improvements in the art of radio communications, and more specifically discloses improved means for damping out parasitic oscillations such as occur in certain types of radio circuits.

This is a division of the applicant's co-pending application Serial No. 318,194 filed November 9, 1928, Patent No. 1,785,819, December 23, 1930.

The nature of the problem involved and the application of the proposed improvements will best be understood by immediate reference to the drawings, of which Figure 1 discloses in schematic form a certain well-known type of radio receiving circuit embodying the improved damping feature, while Fig. 2 discloses a portion of the circuit of Fig. 1 in a form better adapted to explain the circuit operation. Figs. 3 and 4 show schematic circuits adapted to better disclose the broad principle underlying the invention. Figs. 5 and 6 indicate the method of adapting the damping circuit to certain closed core types of coils.

Fig. 1 discloses a radio receiving circuit having one stage of tuned radio frequency amplification, a detector and head-phones for reception of the signal. The waves impinging upon the antenna 26 are impressed upon the amplifier tube 5 by means of the tuned circuit 24. The output of the amplifier tube is impressed upon the detector tube 13 by means of autotransformer 7 associated with tuned circuit 10 in the grid circuit of tube 13. The head-phones 14 for reception are connected in the plate circuit of detector tube 13, as shown.

As is well known for a circuit of the type shown in Fig. 1, in the absence of any neutralizing means, there is a tendency for sustained high frequency oscillations to be set up in the amplifier stage due to the interaction between the plate and grid circuits of tube 5 resulting from the coupling effect through the grid-plate capacity of tube 5. To avoid this tendency to oscillate at high frequency, the neutralizing condenser C_2 is connected in the circuit of Fig. 1 as shown.

Fig. 2 furnishes a clearer picture for comprehending the action by which the sus-

tained oscillations are set up and neutralized. Fig. 2 shows only the amplifier stage of Fig. 1, omitting the D. C. batteries utilized for obtaining the grid and plate potentials and for lighting the tube filaments. In Fig. 2, windings 3 and 4 of coil 27 are drawn schematically to show the mutual inductance between windings and also the leakage inductances L_1 and L_2 of these windings. The grid-plate capacity of tube 5 is shown in dotted lines by condenser C_3 . Assuming for the moment that switch 9 is closed and that the neutralizing condenser C_2 is disconnected from the circuit by opening switch 28, as shown, winding 3 in the grid circuit of tube 5, the capacity C_3 , and the inductance L_3 in the plate circuit comprise a tuned circuit adapted to oscillate at a high frequency. And, since a voltage induced in the plate circuit will produce an interactive effect in the grid circuit and vice versa, sustained oscillations will be set up, provided the total loss in the circuit is sufficiently low. For example, if a voltage be induced in L_3 , it will set up a current flowing through winding 3 and condenser C_3 . The potential drop thus set up in winding 3 will impress a voltage on the grid circuit of the tube, thus permitting the building up of sustained oscillations.

If, however, the neutralizing condenser C_2 is connected in the circuit of Fig. 2, as for example, by closing switch 28, conditions are no longer favorable for sustained oscillations, provided the leakage inductances L_1 and L_2 are negligible and C_2 is of suitable capacity. For example, if conductor 15 is connected to the midpoint of winding 27 and capacity C_2 is made equal to C_3 , no oscillations will occur, provided, as assumed, L_1 and L_2 are negligibly small. This is due to the fact that with such an arrangement there is no interactive effect between the plate and grid circuits, i. e., a voltage in the plate circuit will produce no potential in the grid circuit of tube 5, or vice versa, through the medium of tube capacity. This statement is easily demonstrated by considering again a voltage induced in L_3 . With switch 9 closed, such a voltage will cause a current to flow in conductor 15 through winding 3 and condenser 100

C_3 back to the plate circuit. At the same time, an equal and opposite current will flow in winding 4, and through condenser C_2 back to the plate circuit. The opposing currents flowing in windings 3 and 4 will set up equal and opposing fluxes which will annul one another and hence no voltage will be impressed between the grid and filament of tube 5 as a result of the voltage induced in L_3 , 5 on the assumption stated that L_1 and L_2 are practically zero. Thus, a voltage induced in the plate circuit can produce no effect in the grid circuit and hence conditions are not favorable to sustain oscillations. Correspondingly, a current flowing in the oscillatory circuit 24 will produce no interactive effect in the plate circuit of tube 5. A current oscillating in circuit 24 will induce equal voltages in the same direction in windings 3 10 and 4. These voltages will cause a circulating current to flow in the series circuit comprising windings 4 and 3 and capacities C_2 and C_3 . This circulating current, however, will produce no effect in the plate circuit of tube 5, since one side of the inductance L_3 15 is connected between windings 3 and 4 and the other side is connected between capacities C_2 and C_3 . An inspection of the circuit will show that the arrangement constitutes a balanced bridge in which the inductance L_3 is connected across the equipotential points, with the result that the voltages induced in windings 3 and 4 produce no effect in the plate circuit inductance L_3 and hence an oscillatory current in tuned circuit 24 has no tendency to set up sustained oscillations in the tube. 20

The above method of neutralization, however, is satisfactory only when the leakage inductances L_1 and L_2 are negligible. If these leakage inductances are considerable, as is frequently the case, the neutralization, while effecting the desired result at the frequency to which the circuit comprising coil 25 27 and condenser C_1 is tuned, may cause the circuit to break into violet sustained oscillations at very high frequency and thus interfere with perfect reception. To understand this, assume again a voltage induced in L_3 , 30 causing equal and opposing currents to flow through windings 3 and 4. These currents flowing in the closely coupled portions of windings 3 and 4 indicated by M set up equal and opposing fluxes which produce no effect in the grid of tube 5. The current in winding 3, however, in flowing through the leakage inductance L_1 , does impress a voltage across the grid of tube 5 and, if the loss in the circuit to break into violent sustained oscillations will thus be set up. In this case, there will be two circuits oscillating in unison, one comprising winding 3, condenser C_3 and inductance L_3 and the other comprising winding 4, capacity C_2 and inductance L_3 . The tube 5 supplies the power to overcome the loss 35 40 45 50 55 60 65 70 75 80 85 90 95 100 105 110 115 120 125 130

in both these circuits for maintaining the oscillations.

One method of damping out these oscillations which are termed "parasitic oscillations" would be to insert a tuned circuit 8 70 in conductor 15, as is shown by opening switch 9. This circuit 8 is tuned to the frequency of sustained oscillations and, by introducing considerable loss in the oscillating circuits, renders conditions unfavorable for further oscillation. The circuit 8, however, by introducing an impedance into the conductor 15, reduces the degree of neutralization obtainable. 75

Referring now to Fig. 1, it is proposed by 80 the present invention to damp out the oscillations set up in the circuit due to the leakage inductances of windings 3 and 4, by winding on the same core therewith circuit 1, in the manner shown. Circuit 1 comprises a 85 few turns of wire placed near the upper end of coil 3 and likewise a few turns placed on the core near the lower end of winding 4, said windings being connected in the manner shown through a suitable resistance 2. This circuit 1 is adapted to damp out the tendency of the circuit to produce sustained oscillations but to have no effect on the signals impressed upon the circuit from the antenna 90 95 26. A wave train impinging on the antenna 26 will produce voltages in the same direction in windings 3 and 4 and will thus set up additive fluxes in the core of 27. Due to the connection of the upper and lower windings of circuit 1, the fluxes in the core 100 of 27 will induce equal and opposite E. M. F.'s in circuit 1 and hence no current will flow therein. On the other hand, if an attempt is made to set up sustained oscillations in tube circuit 5, as by inducing a voltage in winding L_3 , equal and opposing currents will flow through windings 3 and 4, respectively. The mutual fluxes set up by these currents will annul each other but the leakage fluxes in windings 3 and 4, respectively, being now opposed in direction, will set up additive E. M. F.'s in the upper and lower windings of circuit 1 which will cause a current to circulate in this circuit and permit the dissipation of energy through the medium of resistance 2. By suitably selecting resistance 2, circuit 1 will thus introduce a sufficient loss in the circuits tending to set up sustained oscillations to prevent their occurrence. 110 115 120 125 130

Resistance 2 can, of course, be included as the resistance of the upper and lower windings of circuit 1, i. e., the windings themselves can be of sufficiently small gauge wire to introduce the proper resistance. The proper value of resistance 2 can best be determined by experiment, as it will not suitably damp out oscillations if too high or too low. For example, if the resistance were zero, circuit 1 could dissipate no energy. The same 130

would be the case if the resistance 2 were so high as to constitute an open circuit.

The best location for the upper and lower windings of circuit 1 on the straight core type 5 of winding, as shown in Fig. 1, is best determined by experiment for each different type of coil. For experimental coils which have been tried out using this method of neutralization, the upper winding has been placed 10 about one-sixteenth of an inch above winding 3, and the lower winding the same distance below winding 4. This has given satisfactory results although it is probable that optimum effects would be obtainable with 15 the upper winding superimposed on winding 3 about one-third of the distance from the top and with the lower winding over winding 4 about one-third of the distance from the bottom.

20 As was brought out above, the amplifier stage of Fig. 1 constitutes a balanced bridge with winding 3 and the grid plate capacity in one balancing arm, and with winding 4 and the neutralizing condenser C_2 in the opposite 25 balancing arm. The circuit of Fig. 1 is therefore merely a specific application of the generalized circuit shown in Fig. 3.

Referring to Fig. 3, generalized impedances 30 and 33 replace the grid-to-plate capacity of the tube and the neutralizing condenser of Fig. 1, respectively. Windings 26 and 28 replace winding 3 of Fig. 1, and windings 27 and 29 replace winding 4. An antenna circuit of Fig. 1 is replaced in Fig. 3 35 by impedance 25 and input winding 34 inductively coupled to windings 26 and 27. The auxiliary circuit 1 is shown the same in both figures.

The leakage inductances of windings 3 40 and 4 of Fig. 1 are shown in Fig. 3 as separate windings 28 and 29 distinct from windings 26 and 27 as is indicated by the separate cores. This is merely to present the more 45 generalized case, since the operation of the circuit of Fig. 3 is the same whether the auxiliary coils 30 and 31 couple separate coils 28 and 29, as shown or whether they couple merely the leakage fluxes of the inductively 50 coupled windings 26 and 27, in which latter case, of course, windings 28 and 29 would be omitted.

The circuit of Fig. 3, as will be seen by inspection, is a device for selectively transferring energy between certain branches of 55 the network. For example, with the coils wound as shown, and, assuming the bridge to be balanced, a voltage active in series with impedance 25 produces no effect in impedances 35 and 36, but does deliver energy to impedances 32 and 33. On the other hand, a voltage active in 35 produces no effect in impedance 25, but does deliver energy to impedances 32, 33 and 36. For the final case, a 60 voltage active in series with 36 delivers no

energy to 25, but does deliver energy to impedances 32, 33 and 35.

It will thus be seen that in addition to the specific use pointed out in connection with Fig. 1, the generalized circuit arrangement of 70 Fig. 3 involving the principle of operation of Fig. 1, will find general application wherever it is desired to selectively transmit energy between from three to five separate impedances.

75 Fig. 4 discloses the generalized circuit of Fig. 3 but with the difference that a closed core type of transformer is employed and the leakage inductance of the transformer windings in the balancing arms is utilized for 80 transferring energy to the auxiliary circuit. The transformer windings in the balancing arms of the bridge are shown at 38 and 39. These windings are symmetrically placed on the core 40. The auxiliary circuit 1 in this 85 case comprises a closed winding extending about the outer confines of the core, as shown.

The selective characteristics of this circuit are shown as follows: With a voltage active 90 in series with impedance 25 equal currents are caused to flow in windings 38 and 39 in such direction that the fluxes are equal and additive, as shown by arrows 20. It will be seen from an inspection of Fig. 4 that for 95 this case, the total flux cutting the auxiliary winding 1 is zero and hence no voltage is induced therein. On the other hand, with a voltage active in series with impedance 35 equal currents flow in windings 38 and 39, 100 producing opposed fluxes in the core as shown by arrows 21. The mutual fluxes annul one another, but the leakage fluxes being now in the same direction through the auxiliary winding 1 as shown by the arrows 21, 105 induce a resultant voltage in circuit 1, causing a current to flow therein.

A specific application of this generalized 110 case may be pointed out by referring again to Fig. 1. Suppose in the circuit arrangement of Fig. 1, the received signal impinging on the antenna contained only the carrier side band and it were desired to introduce the carrier demodulating frequency into the receiving circuit in such manner that it would not 115 be radiated from the antenna. This could be accomplished quite simply with the circuit arrangement shown by merely connecting a source of suitable carrier frequency in the auxiliary circuit 1. The carrier current thus 120 applied to transformer 27 through the windings of the auxiliary circuit would set up equal and opposing currents in windings 3 and 4. The resultant mutual fluxes would 125 annul each other and, hence, no voltage would be induced in the antenna circuits. On the other hand, the currents opposed in windings 3 and 4 would flow in the same direction through winding L_3 and would thus impress 130 the carrier frequency upon the detector tube.

along with the received side band permitting effective demodulation.

Fig. 5 shows the location of the auxiliary circuit 1 for a toroidal core type of coil adapted for use in a circuit arrangement such as is shown in Fig. 1. The manner in which the coil of Fig. 5 would be connected in the circuit of Fig. 1 is indicated by the terminals 15, 16 and 17, which are the same as for the corresponding terminals of coil 27 of Fig. 1.

10 The voltage impressed across the terminals 15 and 17 of Fig. 5 would produce additive fluxes in the core, as shown by the arrows 20, and thus the total flux linking the dissipative circuit 1 would be zero, and hence no energy would be dissipated by such circuit in this case. On the other hand, for currents flowing in at terminals 16, and out at terminals 15 and 17, or the reverse, opposing fluxes would be set up in the core, as indicated by the arrows 21. In this case, the mutual fluxes would annul one another, but the leakage fluxes would cut the dissipative circuit 1 and thus cause energy to be expended therein.

25 Fig. 6 shows a torusolenoид type of coil so-called, in which the connections 15, 16 and 17 are the same as indicated for coil 27 of Fig. 1. In this case, with a current flowing in over lead 15, and out over lead 17, the fluxes are additive, as shown by the arrows 20, and hence the total flux cutting the dissipative circuit 1 is zero and no loss is introduced thereby. On the other hand, for currents flowing in over lead 16 and out over leads 15 and 17, or the reverse, opposing fluxes are set up in the core, as indicated by the arrows 21, thus causing the resultant leakage flux to cut the dissipative circuit 1, thereby introducing a loss.

40 Each new type of winding, of course, presents its own problem as to the best location for the auxiliary winding. The general rule to be followed in all cases, however, is to so locate the neutralizing winding that it will be linked with the maximum possible leakage flux. Also, the auxiliary circuit should be symmetrically placed with respect to the coil windings so that it will be linked by the same portion of the main flux from each winding, thus insuring that it does not absorb energy from the main circuit.

45 It is to be understood, of course, that the application of the auxiliary circuit is not to be restricted to the circuit arrangement of Fig. 1, but may be used generally wherever applicable in accordance with the principles outlined in connection with Fig. 3.

50 In the claims the term "closed winding" signifies a winding the terminals of which are connected together.

55 What is claimed is:

1. A translating device comprising in combination, a balanced bridge having a secondary transformer winding in each balancing arm, a primary circuit inductively cou-

pling said secondary windings, an auxiliary transformer individual to each said balancing arm with a primary winding in series therewith, a series connection for the secondaries of said auxiliary transformers such that a voltage active in said primary circuit first mentioned induces opposed voltages in said auxiliary secondary windings, whereas a voltage active in the bridging arm of said bridge induces additive voltages in the auxiliary secondary windings. 75

2. A translating device comprising in combination, a balanced bridge containing a secondary transformer winding in each balancing arm, a primary circuit inductively coupling said secondary windings, an auxiliary circuit inductively coupling the leakage inductance of both said secondary windings in such manner that a voltage active in said primary circuit is ineffective in the auxiliary circuit, whereas a voltage active in the bridging arm of said bridge induces a voltage in the auxiliary circuit. 80

3. A translating device comprising in combination, a balanced bridge containing a secondary transformer winding in each balancing arm, a primary circuit inductively coupling said secondary windings, an auxiliary circuit comprising a small inductance individual to each said secondary winding and inductively coupling the leakage inductance thereof, a series connection for said small inductances such that a voltage active in said primary circuit induces equal and opposed voltages in said auxiliary circuit whereas a voltage active in the bridging arm of said bridge induces equal and additive voltages in said auxiliary circuit through the medium of said leakage inductances. 95

4. In a receiving circuit of the type disclosed having the filament of an amplifier tube tapped to an intermediate point of the input coil with the terminals of the latter connected to the grid and through a neutralizing condenser to the plate, respectively, means for supplying the carrier demodulating frequency at the receiving circuit, comprising an auxiliary circuit containing a source of suitable carrier current, said auxiliary circuit being inductively coupled to the grid and plate circuits, respectively, in such manner that said carrier frequency is not effective in the antenna circuit but is effectively impressed upon the demodulating means associated with said receiving circuit. 105

55 In testimony whereof, I have signed my name to this specification this 15th day of March, 1930.

HAROLD C. SILENT.
